UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,209,126.

Specification of Letters Patent. Patented Dec. 19, 1916.

Application filed September 17, 1912. Serial No. 720,765.

To all whom it may concern:

- Be it known that I, CORNELIUS B. CORCORAN, a citizen of the United States, residing in the borough of Bronx, city of New York, in the county of New York and State of New York, have invented certain new and useful Improvements in Type-Writing Machines, of which the following is a specification.
- 10 This invention relates to improvements in paper alining devices for typewriting machines, such for instance as shown in the patent to Harry S. McCormack, No. 963,629, dated July 5, 1910.
- 15 Heretofore when a written sheet was inserted a second time, it was necessary to adjust the sheet at its top and side edge, to bring the first written line to the printing position, after which the platen had to be
- 20 turned until the first blank line appeared.

An object of my invention is to avoid such manipulation of the paper, and to this end I arrange to guide the work sheet by means of both its side edges, and initially 25 adjust the paper directly at the line to be written upon. The aliner is adaptable to sheets of various widths. The top gage may, however, be retained for use with certain kinds of work, in connection with either one 30 or both of the side gages.

The alining table may comprise plates overlapped to form a continuous support for the work-sheet, and each having along its outer edge a gage for the side edge of 35 the work-sheet, said plates being separately adjustable in the direction of the platen axis to adjust the position of the side edges of the work-sheets and also to accommodate work-sheets of different widths. The upper 40 and lower edges of the plates may be formed with telescoping beads, a set screw being provided to lock the plates together in adjusted position. The alining table is supported by brackets, one adjustably connected 45 to each plate, permitting adjustment of the table toward and from the platen, the brackets slidably mounted on a rod parallel with the platen, and a latch pivoted to one bracket to engage notches in the said rod to 50 hold the table in adjusted position.

Other objects and advantages will herein-after appear.

In the accompanying drawings, Figure 1 is a top plan view of the aliner mounted 55 upon a platen frame. Fig. 2 is a cross sec-

tional view of Fig. 1. Fig. 3 is a perspective view, showing the method of mounting the aliner and locking against accidental displacement. Fig. 4 is a section along the broken line as indicated by the arrows in Fig. 2.

The usual typewriter platen frame 1 comprises paper table 2 and ends 3, 4, which carry journals for the axle 5 of platen 6. Between the ends 3, 4, extends a shaft 7, 65 and mounted upon this shaft by means of brackets 8 and 9 are two telescoping plates 10, 11, which may be extended or closed to make their opposite side gages 12 fit sheets of various widths.

Since the side gages 12 are of considerable length, it is practicable to use these gages alone for gaging or justifying the work sheet, without the aid of the top gage 14, in many cases; the side gages being relatively adjusted so that the sheet will just fit between them. By means of these side gages, which are at right angles to the platen, the horizontal lines of printing or writing on the work sheet are brought parallel with the platen. Hence it is practicable to introduce the sheet into the machine and place it between the side gages and then at once by advancing or retracting the sheet to bring the first blank line directly to the 85 printing point, without a preparatory gaging of the top edge of the sheet to the top gage, although, if desired, the top gage may also be employed, as heretofore.

The aliner is set by first adjusting the 90 gage 12 of the left alining plate 10, as the left margin is generally kept uniform on all sheets. The right alining plate 11 is then drawn out of the plate 10, until its gage 12 is brought to register with the right edge of 95 the sheet. The two alining plates may now be secured by tightening the thumb screw 15, which clamps the plates together.

One alining plate 11 extends beneath the other plate 10, to telescope with it. This 100 gives a continuous paper rest or table between the two side gages 12, upon which the operator may press his fingers while locating a sheet. The alining plates 10 and 11 are held in proper relation to each other 105 by telescoping beads 16 and 17 on the plates 10 and 11 respectively, said beads being provided on both the upper and lower edges of the plates; the beads 16 forming guideways for the beads 17 to slide in. Each of the

alining plates 10, 11, is supported by only one bracket 8 or 9 at its outer end, but the telescoping beads 16, 17 coöperate to serve as supports for the inner ends of the plates, 5 and prevent sagging.

A dog 18 pivoted at 19 to the bracket 8 is adapted to enter any one of a series of notches 20 in shaft 7 and prevents lateral displacement of the alining plates. This dog 10 18 is normally held in locking position by a spring 21, and may be withdrawn by means of a finger piece 22 whenever it is desired to move the left alining plate. The right alining plate 11 moves together with the left 15 alining plate 10, being locked thereto by thumbscrew 15, but when this screw is loosened, each plate may be adjusted relatively to the other.

The brackets 8, 9, are mounted upon the 20 rod 7 by means of yokes 23. A spring 24 seated in each yoke, presses a key into a groove 25 in the rod, whereby the alining table 10, 11 is held firmly, but may be swung around the rod or shaft if desired, the 25 brackets being journaled on the rod.

Variations may be resorted to within the scope of the invention, and portions of the improvements may be used without others.

Having thus described my invention, I 30 claim:

1. The combination, in a typewriting machine, with the platen frame and the platen thereof, of a paper alining table arranged over the platen, said table consisting of two 35 members arranged at their upper and lower edges with telescoping flanges for lateral adjustment, a gage on the outer edge of each member, and means associated with one of said flanges for holding said plates in adjusted position.

2. The combination, in a typewriting machine, with a platen frame and platen thereof, of a paper alining table adapted to be arranged over the platen, said table consisting 45 of two members arranged at their edges with telescoping flanges, a slot in the outer of one of said pairs of flanges, and a pin upon the other flange of the same pair, said pin adapted to slide in said slot, and means on said pin 50 for clamping the two together, each of said members being arranged with a gage on its outer side.

3. The combination, in a typewriting machine, with a platen frame and platen there- 55 of, of a shaft mounted parallel to said platen, a bracket mounted toward each end of said shaft and adapted to slide thereon, a plate carried by each of said brackets, the two plates being arranged in telescopic relation 60 to extend above and obliquely rearward from the platen, a gage on the outer edge of each of said plates, and means on said plates for holding them in adjusted position.

4. The combination, in a typewriting ma- 65 chine, with a platen frame and platen there-

of, of a shaft extending parallel with the platen and to the rear thereof, brackets carried by said shaft one at each end thereof and adjustable lengthwise of said shaft, means between the bracket and the shaft 70 whereby the brackets are kept from turning with reference to the shaft, a plate adjustably mounted on each of said brackets, said plates being provided with telescoping flanges for lateral adjustment, each plate being provided with a gage on its outer edge, and means in connection with one of the flanges for holding said plates in lateral adjustment.

5. The combination, in a typewriting machine, with a platen frame and platen thereof, of a shaft extending parallel with the platen and a little above it, brackets mounted on said shaft and adjustable lengthwise of said shaft, means between the shaft and 85 bracket for preventing the brackets from turning on said shaft, a plate mounted on each of said brackets and extending upward and rearwardly from the platen, said plates arranged with telescoping flanges to constitute a paper alining table, a gage on the outer edge of each of said plates, means for holding said plates in adjustable relation to prevent their movement with respect to each other, and means on said shaft for preventing 90 the movement of the plates which constitute the table, as a whole with reference to said shaft.

6. The combination, in a typewriting machine, with a platen frame and platen thereof, of a paper alining table made in two parts, said parts being telescopically adjustable laterally, a flange on the outer of each of said parts, means for holding the parts in any lateral adjustment, a shaft parallel to the platen, brackets slidable along the shaft, each bracket carrying one of said parts, said shaft being provided at one end with a ratchet, and a dog mounted on one of said parts for engagement with said ratchet 110 whereby the paper table may be locked as a whole in any predetermined position with respect to the platen.

7. In combination, of a typewriting machine, with a platen frame and platen there- 115 of, of a paper alining table arranged above the platen and extending rearwardly therefrom obliquely, said table consisting of two members telescopically arranged at their edges for lateral adjustment, each of said members carrying a gage at its outward edge, and one of said members carrying a gage at the top, means connected with one of the pairs of telescopic members for locking 120 the members in any adjustment, a shaft on 125 a parallel with the platen, brackets mounted on the shaft, each of said brackets being connected to one of said table members and both being movable along said shaft, a ratchet on said shaft at one end thereof, and 130

a spring pressed pawl carried by one of said brackets for engagement with said ratchet to hold the table as a whole in any lateral position with respect to the platen, whereby
 5 the members of the table may be adjusted to accord with the width of a sheet of paper, the table as a whole may be adjusted to suit the location of the writing on the sheet, and the sheet may be adjusted with respect to the
 10 top gage to insure accurate alinement.

8. The combination with a platen frame and a platen thereon, of an alining device comprising members relatively adjustable in the direction of the platen axis and having telescoping guides extending parallel with the platen axis, whereby said members are guided in their adjustment, each member having a gage for the side edge of the work-sheet, means to lock said members together in adjusted position, and means for supporting said alining device on the platen frame for adjustment in the direction of the platen axis.

9. The combination with a platen frame and a platen thereon, of an alining device comprising members relatively adjustable in the direction of the platen axis and having telescoping guides extending parallel with the platen axis, whereby said members are guided in their adjustment, each member having a gage for the side edge of the work-sheet, means to lock said members together in adjusted position, and means for supporting said alining device on the platen frame for adjustment in the direction of the platen axis and also in a direction perpendicular to the platen axis.

10. The combination with a platen frame and a platen thereon, of an alining device comprising members each having a gage for the edge of a work-sheet, a rod parallel with the platen, brackets each connected to one of said members and slideable on said rod to permit relative adjustment of said members, means to lock said members together, whereby said device may be adjusted as a unit, and a latch to lock said device against movement longitudinally on said rod.

11. In a paper-alining table, the combination of sliding plates overlapped to form a continuous telescopic support and each provided with a side gage, said plates adjustable laterally to vary the distance between said gages, the upper and lower edges 55 of the plates being rolled to form telescoping guides extending in the direction of said adjustment, and means to lock said plates in laterally adjusted position.

12. In a typewriting machine, the combination with a revoluble platen, of a work-sheet alining table consisting of two over-

lapping plates having side gages, means slidably supporting said plates in advance of the delivery portion of the platen, and cooperative guiding members formed upon 65 both upper and lower edges of both of said plates to guide them in relative sliding movements.

13. In a typewriting machine, the combination with a rotary platen, of a paper alining table therefor comprising sections, means extending along the opposite edges of said sections forming a slideable telescopic connection between the edges of said sections rendering them easily adjustable in a single 70 operation toward and from each other, and means for holding said sections in adjusted position, said sections carrying gages for the side edges of a work-sheet, and being adjustable together along the platen, whereby said table may be adjusted any width to suit the width of a sheet and may also be adjusted in position to suit the location of the line with respect to the sheet.

14. The combination with a revoluble 85 platen, of an alining table mounted over the platen and having a rear gage against which to adjust the leading edge of a sheet and also having at one side a gage for a side edge of the sheet, and a telescopic extension 90 connected with said table for relative adjustment in a direction of the axis of the platen to form an extended table, said extension having a gage for the opposite side edge of the sheet.

15. The combination with a revoluble platen, of an alining table mounted over the platen and having a rear gage against which to adjust the leading edge of a sheet and also having at one side a gage for a side edge of the sheet, and a telescopic extension connected with said table for relative adjustment in a direction of the axis of the platen and having a gage for the opposite side edge of the sheet; said table with 100 its extension being also bodily adjustable 105 longitudinally of the platen.

16. The combination with a revoluble platen, of an alining table mounted over the platen and having a rear gage against which 110 to adjust the leading edge of a sheet, and also having at one side a gage for a side edge of the sheet, a telescopic extension connected with said table for relative adjustment in a direction of the axis of the platen and having 115 a gage for the opposite side edge of the sheet, and means to secure said extension in various adjustments relatively to said table.

CORNELIUS B. CORCORAN.
